UNITED STATES PATENT OFFICE.

GIOVANNI MAURO, OF PATERSON, NEW JERSEY, ASSIGNOR OF ONE-THIRD
TO GEORGE HARRIS AND JOSEPH DI CARLO, OF SAME PLACE.

CAR-FENDER.

SPECIFICATION forming part of Letters Patent No. 628,275, dated July 4, 1899.

Application filed March 7, 1899. Serial No. 708,154. (No model.)

To all whom it may concern:

Be it known that I, GIOVANNI MAURO, a subject of the King of Italy, and a resident of the city of Paterson, Passaic county, New Jersey, have invented a new and useful Improvement in Car-Fenders, of which the following is a specification.

The object of this invention is to provide a fender or guard for cars, whether propelled by steam, electricity, or other power, which will pick up and carry any person or object which the car may encounter while in motion and hold said person or object until the car can be brought to a standstill without serious injury to the person or other object so picked up.

It is also a part of the object of my invention to so arrange the guard or fender that it may be closed up compactly within a small space and be easily removed from one end of the car to the other when required.

My invention consists in the peculiar construction, arrangement, and combination of parts, which will be hereinafter described in the specification and claims, reference being had to the accompanying drawings, which form a part of the specification, and in which similar letters of reference indicate like parts in the different figures.

The framework of my fender consists of three principal parts, which are pivotally connected in such a manner that the three sections may be folded together as shown in Figure 3 of the drawings. Over these sections of the frame is secured a netting apron of suitable material, but preferably of fibrous material. On the front of the fender is secured a contact-cushion of yielding material calculated to soften the blow when the fender strikes a person or other object. The fender is provided with eyes whereby it is hung upon hooks which are secured to the car-body.

In the accompanying drawings, Fig. 1 is a side view of my fender when open and hung onto the front end of the car. Fig. 2 is a plan view of the same when open, and Fig. 3 is a side view of the same when closed.

The upper, middle, and lower sides a , a' , and a'' of the frame-sections are pivotally connected by the connecting-rods b' and b'' . An upper connecting-rod b connects the two up-

per sides of the upper section of the frame, and a lower connecting-rod b^3 connects the lower-section sides at their outer extremities. The netting apron h is provided with side chains g and is strung from the upper connecting-rod b to the lower connecting-rod b^3 .

A controlling device consisting of the two limbs f' and f'' , hinged together by a hinge f , straightens out when the fender is opened and keeps the fender opened, as shown in Figs. 1 and 2, until the fender comes in contact with some object with sufficient force to cause said controlling device to sink where hinged and the front or outer end of the fender to be elevated or raised, when the tension-springs c , which connect sections a' and a'' , help to draw the front or lower section upward. When the front section is thus drawn upward, the said controlling device or limbs f' and f'' are lowered and rest upon the connecting-bars, forming a cradle to receive and hold the person or other object which is picked up by the contact of the fender. The inner limb f'' of the controlling device is provided with a guide-loop which surrounds the connecting-rod b' . Said guide-loop is of sufficient length to permit the controlling device to be lowered until it rests on the connecting-rods, as above mentioned, and to permit said device to be raised until it is almost level or until the two limbs of the device nearly form a straight line. The outer extremity of the limb f'' is loosely connected with the connecting-rod b^3 , so as to permit the raising and lowering of the said controlling device. The hinge f is adapted to prevent the limbs f' and f'' from rising or bending upwardly where hinged together farther than is shown in Fig. 1 of the drawings. The guide-loop f^3 , the hinge f , and the tension-springs c cause the controlling device to remain rigid enough to keep the sections of the fender extended or open, as shown in Fig. 1, until the fender comes in contact with some object, when the controlling device being slightly out of a straight line is lowered by the outer section of the fender being elevated by such contact and by the tension of the springs c . The hooks d and d' are secured to the front and rear portions of the car-platform, and the upper section of the fender-frame is provided

with eyes to fit on said hooks. This construction permits the fender to be folded up, as shown in Fig. 3, when the fender may be removed with facility from one end of the car 5 to the other. The front of the fender is provided with a contact-cushion *k*, which may consist of canvas with a projecting rubber covering or other suitable yielding material.

With this description of my invention, what

10 I claim is—

1. In a guard-fender for cars, the combination with the car of a fender consisting of three sections pivotally connected by connecting-rods extending transversely across 15 the fender, tension-springs connecting the middle and lower sections of fender, a contact-cushion consisting of yielding material secured to the front of the fender and a controlling device consisting of two members 20 two ends of which are connected by a hinge, the one end of the outer member being loosely secured with a connecting-rod at the front of the fender, the other end of the inner member being provided with a guide-loop, which 25 passes around an inner connecting-rod of fender, said controlling device being located midway between the sides of the fender, substantially as and for the purposes described.
2. In a life-saving guard for cars, the combination with the frame consisting of three 30 sections pivotally connected as to fold together, of side tension-springs connecting the middle and lower sections of the frame and a controlling device located midway be-

tween the sides of the fender and consisting 35 of two members connected by a hinge, one end of one member loosely secured to the front of fender-frame and one end of the other member being provided with a guide-loop, which passes around a transverse connecting-rod of fender-frame and limits the movement of the controlling device, substantially as and for the purposes specified. 40

3. In a life-saving guard for cars, the combination with the frame consisting of three 45 sections pivotally connected as to fold together, of side tension-springs connecting the middle and lower sections of the frame and a controlling device located midway between the sides of the fender and consisting of two 50 members connected by a hinge, one end of one member loosely secured to the front of fender-frame and one end of the other member being provided with a guide-loop, which passes around a transverse connecting-rod of 55 fender-frame and limits the movement of the controlling device, a contact-cushion secured to the front of fender and a netting apron secured to fender-frame, the fender-frame being provided with eyes, the whole being 60 adapted to being hung on suitable hooks secured either to the front or rear of a car, substantially as and for the purposes specified.

GIOVANNI MAURO.
